United States Patent Office

Des. 187,474
Patented Mar. 22, 1960

187,474

DICTATING MACHINE

Heinz Hubner, Furth, Bavaria, Germany, assignor to
Grundig Elektro-Mechanische Versuchsanstalt,
Furth, Germany, a corporation of Germany

Application June 6, 1958, Serial No. 51,228

Claims priority, application Germany March 6, 1958

Term of patent 14 years

(Cl. D26—14)

Fig. 1 is a front perspective view of a dictating machine, showing my new design; and
Fig. 2 is a rear perspective view thereof.

The broken lines appearing in the drawing are for illustrative purposes only.

I claim:

The ornamental design for a dictating machine, as shown and described.
